CIGARETTE LIGHTER OR SIMILAR ARTICLE

Yoshio Kanamaru, Tokyo, Japan, assignor to Kanamaru
Shoten, Ltd., Tokyo, Japan

Filed Oct. 20, 1965, Ser. No. 87,633

Term of patent 14 years

(Cl. D48—27)

FIG. 1

FIG. 2

FIG. 4

FIG. 1 is a perspective view of a cigarette lighter or similar article embodying the present design;

FIG. 2 is an end view thereof;

FIG. 3 is a top view thereof; and

FIG. 4 is a side view thereof.

The characteristic features of my design for the cigarette lighter as shown reside in the control elements and windshield, having the configuration shown.

I claim:

The ornamental design for a cigarette lighter or similar article, as shown and described.
